WHIP MACHINE

Bruce Carvel, Cranbury, N.J., assignor to
Carvel Corporation, Yonkers, N.Y.

Filed May 23, 1972, Ser. No. 256,217

Term of patent 14 years

Int. Cl. D15—08

U.S. Cl. D55—1 E

FIG. 1

FIG. 2

FIG. 3

FIG. 1 is a front perspective view of a whip machine showing my new design.

FIG. 2 is a top plan view thereof.

FIG. 3 is a rear elevational view thereof.

The side opposite the side shown in FIG. 1 is identical thereto.

I claim:

The ornamental design of a whip machine, substantially as shown and described.
